UNITED STATES PATENT OFFICE

165,486

STOCKING

Richard E. Schletter, Cheltenham Township,
Montgomery County, Pa., assignor to Signature
Hosiery Company, North Wales, Pa., a corporation of Pennsylvania

Application October 5, 1948, Serial No. 148,973

Term of patent 14 years

(Cl. D47—7)

To all whom it may concern:

Be it known that I, Richard E. Schletter, a citizen of the United States, residing in Cheltenham Township, county of Montgomery, Commonwealth of Pennsylvania, have invented a new, original, and ornamental Design for a Stocking, of which the following is a specification, reference being had to the accompanying drawings, which form a part thereof.

I claim:

The ornamental design for a stocking, as shown.

RICHARD E. SCHLETTER.
